CLAIM

The ornamental design for the cabinet bar pull, as shown and described.

DESCRIPTION

FIG. 1 is a front perspective view of the cabinet bar pull design showing my new design.

FIG. 2 is a front view of the cabinet bar pull.

FIG. 3 is a rear view of the cabinet bar pull.

FIG. 4 is a left side view of the cabinet bar pull.

FIG. 5 is a right side view of the cabinet bar pull.

FIG. 6 is a top view of the cabinet bar pull.

FIG. 7 is a bottom view of the cabinet bar pull; and,

FIG. 8 is a rear perspective view of the cabinet bar pull.

Any shading and cross-hatching are not features of the design but are utilized to illustrate the surface contours of the cabinet bar pull design in the drawings.

The broken lines in FIG. 3 and FIG. 8 just show the inside shape for illustrative purposes only and not the part of the claimed design.
